UNITED STATES PATENT OFFICE.

WILLIAM J. RUTTLEDGE, OF OTISVILLE, MICHIGAN.

TRUSSLED LADDER.

SPECIFICATION forming part of Letters Patent No. 673,969, dated May 14, 1901.

Application filed March 7, 1901. Serial No. 50,173. (No model.)

To all whom it may concern:

Be it known that I, WILLIAM J. RUTTLEDGE, a subject of the King of Great Britain, residing at Otisville, in the county of Genesee and 5 State of Michigan, have invented certain new and useful Improvements in Trussed Ladders, of which the following is a specification, reference being had therein to the accompanying drawings.

This invention relates to new and useful improvements in ladders, and more particularly to that class of ladders known as the "trussed fire-ladder," and has for its object to make a ladder of great strength without 15 materially increasing the weight of the same, a further object being to construct a ladder which, although comparatively light, shall be so effectually stayed as to be especially serviceable for the use of firemen and whereby 20 the stays and metallic parts shall be so insulated as to avoid all danger of shocks by electricity should the ladder come in contact with a live wire.

To this end the invention consists in the use 25 of truss-rods laid in the wooden truss members and adapted to be placed under tension; and it consists in providing a suitable insulating-covering for the same and in the employment of means for tensioning said rods, and 30 the invention consists, further, in the construction, arrangement, and combination of parts, all as more fully hereinafter described, and shown in the accompanying drawings, in which—

Figure 1 is a side elevation of my improved ladder. Fig. 2 is a plan view thereof. Fig. 3 is a vertical section through the opposite ends of one of the side members. Fig. 4 is a 35 sectional elevation thereof with the insulating-cap removed. Fig. 5 is a section on line xx , Fig. 3. Fig. 6 is a section on line yy , Fig. 3. Fig. 7 is a section on line zz , Fig. 1. Fig. 8 is a similar section, showing my construction of ladder without the insulating- 40 cap.

As shown in the drawings, A A represent the parallel legs of a ladder, which are connected in the usual manner by transverse rounds A'.

B B represent the trussed bars or truss-frame pieces, which are bowed downwardly from and have their ends rigidly connected with the end portions of the legs A A in a man-

ner hereinafter described. As indicated in the drawings, the legs and trusses are connected 55 in the usual manner and at desirable intervals by struts or blocks a.

In joining the end portions of the trusses and legs I employ metallic clamping-yokes C D, which are of substantially stirrup or 60 U form, as indicated in the drawings.

b represents parallel grooves formed in the outer face of the wooden truss members, and c represents truss-rods laid in said grooves, adjustably secured at their lower ends by means 65 of the nipples d in the bottom of the yoke C, while their upper ends are brazed or otherwise secured to a grooved plate e, with its upper end in proximity to a shoulder f, formed on the clamping-yoke D, and g is a bolt having 70 a screw-thread engagement with said plate, whereby both of said truss-rods may be adjusted at one and the same time, while if it is desired to adjust but one of said rods it is done by means of the nipples d at the 75 opposite end.

E is an insulating cap or strip having the parallel grooves h formed therein, adapted to fit over the truss-rods and cover the same, so that there is no chance for an electric wire 80 coming in contact therewith. This cap is held in place at intervals intermediate its length by means of the plates i and the bolts j, passing through said plate, cap, truss, strut, and member A of the ladder, as shown in Fig. 85 7. I may, however, where it is not desired, dispense with the use of the insulating-molding, in which event I employ plates k, likewise secured in position at intervals apart, as shown in Fig. 8.

The clamping-yokes C D are adapted to fit over the lower and upper ends of the legs, truss, and cap of the ladder, respectively, to form a solid structure, being held in place by bolts l, and l' represents apertured ears formed 95 on opposite sides of said yokes, in which the tapering pins m are adapted to be inserted, a suitable hole having first been bored through the meeting faces of the legs and truss at that joint. These pins are provided with a squared 100 head at one end and a screw-thread at the other end, adapted to have a screw-thread engagement with one of said ears, so that as the parts become dried out or loose by simply setting up on these pins all slack is taken up. 105 n n' are points formed on the lower end of

- the yoke C, the point n' being detachable therefrom and is formed with a lug n^2 , adapted to fit in an aperture formed in said yoke, being held in place by means of one of the bolts 5 l. The yoke D is also provided with a plate o, adapted to cover the head of the adjusting-screw g, and is held in place by means of the lug o', fitting in an aperture in said yoke and one of the bolts l.
- 10 P is a strip of rubber or other insulating material interposed between the inner face of the clamping-yoke CD and the contacting parts of the ladder, so that all danger of completing an electric circuit between the component parts and the ladder is avoided, which is such a great source of danger in all ladders where metallic trussing is resorted to, a further advantage being that by reason of my truss rods or wires being covered they are not so readily affected by a change in temperature as when exposed, let alone, as before stated, the advantage of avoiding all danger of shocks to the men by electricity, and I have found that by actual experiment I can support three times the weight on my ladder with the use of my construction of truss-rods than without them without materially increasing the weight of the ladder, and by means of the individual adjustment I am enabled to tension these rods exactly right at all times.
- 15 What I claim as my invention is—
1. In a trussed ladder, the combination with the legs, rounds and trusses, said legs and trusses having the meeting faces of their adjoining end portions provided with recesses forming the complementary halves of a transverse aperture, of metallic clamping-yokes adapted to embrace the united end portions of said trusses and legs, one arm of said yoke 20 being provided with ears projecting on opposite sides and registering with said transverse aperture, a taper pin passing through said ears and aperture, and having a screw-thread engagement with one of said ears and bolts 25 connecting the arms of said yokes and passing through said trusses and legs, substantially as and for the purpose specified.
  2. In a trussed ladder, the combination with the legs, rounds and trusses, of metallic clamping-yokes adapted to embrace the united end portions of said trusses and legs, grooves formed in said trusses, truss-rods laid in said grooves and means for putting said truss-rods under tension.
  3. In a trussed ladder, the combination with the legs, rounds and trusses, of metallic clamping-yokes adapted to embrace the united end portions of said trusses and legs, grooves formed in said trusses, truss-rods laid in said grooves and means for adjusting said truss-rods individually at one end and jointly at the other end.
  4. In a trussed ladder, the combination of the legs, rounds and trusses, grooves formed in said trusses, truss-rods laid in said grooves, a cap fitting over said truss and having similar grooves adapted to cover said rods and

metallic clamping-yokes adapted to embrace the united end portions of said trusses, caps and legs, and means carried by said yokes 70 for tensioning said rods.

5. In a trussed ladder, the combination with the legs, rounds and trusses of grooves formed in said trusses, truss-rods laid in said grooves, and means for tensioning the same, insulating-strips laid over said trusses and adapted to cover the same, clamping-yokes adapted to embrace the united end portions of said trusses and legs, and insulating material interposed between said united end portions 80 and said clamping-yokes.

6. In a trussed ladder, the combination with the legs, rounds and trusses, transverse apertures formed at the meeting faces of their adjoining end portions, clamping-yokes adapted to embrace the united end portions of said trusses and legs, apertured ears formed on said clamping-yoke projecting on opposite sides of said end portions, registering with said transverse apertures, and pins fitting in 90 said apertures having a screw-thread engagement with one of said ears adapted to take up the slack between said leg and truss members.

7. In a trussed ladder, the combination with the legs, rounds and trusses of grooves formed in said trusses, truss-rods laid in said grooves, insulating-strips laid over said grooves, clamping-yokes adapted to embrace the united end portions of said trusses and legs, and separate means for adjusting said truss-rods at 100 the opposite ends thereof carried by the clamping-yokes.

8. In a trussed ladder, the combination with the legs, rounds and trusses of metallic clamping-yokes, adapted to embrace the united end portions of said trusses and legs, grooves formed in said trusses, truss-rods laid in said grooves, a plate to which said truss-rods are secured, at one end, a screw-bolt swiveled in one of said clamping-yokes and having a 110 screw-thread engagement with said plate and nipples swiveled in the opposite clamping-yoke and having a screw-thread engagement with the opposite ends of said truss-rods.

9. In a trussed ladder, the combination with the legs, rounds and trusses, of metallic clamping-yokes adapted to embrace the united end portions of said trusses and legs, apertured ears formed on said yokes, transverse apertures formed in the meeting faces of said trusses and legs, taper pins fitting in said apertures and having a screw-thread engagement with said ears, and truss-rods secured to said truss members and having an insulated cap for covering the same adapted to 125 be embraced at its opposite ends by said clamping-yokes and means carried by said yokes for tensioning said rods.

In testimony whereof I affix my signature in presence of two witnesses.

WILLIAM J. RUTLEDGE.
